(57) **CLAIM**

The ornamental design for a flexible neck toothbrush, as shown and described.

DESCRIPTION

FIG. 1 is a perspective view, as seen from the top end, front side, of a first embodiment of a flexible neck toothbrush of my new design;

FIG. 2 is a front elevation view thereof;

FIG. 3 is a back elevation view thereof;

FIG. 4 is a right elevation view thereof, the left side being a mirror image of the right side elevation as shown in FIG. 4;

FIG. 5 is a top plan view thereof;

FIG. 6 is a bottom plan view thereof;

FIG. 7 is a perspective view, as seen from the top end, front side, of a second embodiment of a flexible neck toothbrush of my new design;

FIG. 8 is a front elevation view thereof;

FIG. 9 is a back elevation view thereof;

FIG. 10 is a right elevation view thereof, the left side being a mirror image of the right side elevation as shown in FIG. 4;

FIG. 11 is a top plan view thereof; and,

FIG. 12 is a bottom plan view thereof.

The bristles of the toothbrush embodiment of FIGS. 7-12 are shown in broken lines for illustrative purposes only and form no part of the claimed design.
